UNITED STATES PATENT OFFICE.

WILLIAM A. STOLLEY, OF DOWAGIAC, MICHIGAN.

DESIGN FOR A FISH-BAIT BODY.

58,116.

Specification for Design.

Patented June 7, 1921.

Application filed December 27, 1920. Serial No. 433,510. Term of patent 14 years.

To all whom it may concern:

Be it known that I, WILLIAM A. STOLLEY, a citizen of the United States, residing at Dowagiac, in the county of Cass, State of Michigan, have invented a new, original, and ornamental Design for a Fish-Bait Body, of which the following is a specification, reference being had to the accompanying drawing, forming a part thereof.

Figure I is a side view of a fish bait body showing my new design.

Fig. II is a front view thereof.

I claim:

The ornamental design for a fish bait body, as shown.

WILLIAM A. STOLLEY.

Witnesses:

J. T. WELCH,
JOHN HEDDON.
